(57) **CLAIM**

The ornamental design for an electromagnetic stirrer, as shown and described.

DESCRIPTION

FIG. 1 is a top view of an electromagnetic stirrer;
FIG. 2 is a bottom view thereof;
FIG. 3 is a front view thereof;
FIG. 4 is a back view thereof;
FIG. 5 is a right side view thereof;
FIG. 6 is a left side view thereof;
FIG. 7 is a top, right side perspective view thereof;
FIG. 8 is a bottom perspective view thereof; and,
FIG. 9 is another top, right side perspective view thereof.
The broken lines represent environmental subject matter and form no part of the claimed design.
